CLAIM

The ornamental design for a food holding bin, as illustrated and described.

DESCRIPTION

FIG. 1 is a food holding bin showing our new design.

FIG. 2 is an elevational view of a front side thereof.

FIG. 3 is an elevational view of a rear side thereof.

FIG. 4 is a top plan view thereof.

FIG. 5 is a bottom plan view thereof.

FIG. 6 is an elevational view of a right side thereof; and, FIG. 7 is an elevational view of a left side thereof.

The broken lines in the drawings depict portions of the food holding bin that form no part of the claimed design. The claimed design is shown with a symbolic break in its length, width and height. The appearance of any portion of the food holding bin set between the break lines forms no part of the claimed design.
